UNITED STATES PATENT OFFICE.

JOHN HANCOCK AND LEVI RICHARDS, OF PROVIDENCE, RHODE ISLAND,
ASSIGNORS TO DAVID B. CHURCHILL, OF SAME PLACE.

SLEEVE-BUTTON.

SPECIFICATION forming part of Letters Patent No. 249,760, dated November 22, 1881.

Application filed July 11, 1881. (Model.)

To all whom it may concern:

Be it known that we, JOHN HANCOCK and LEVI RICHARDS, of the city and county of Providence, in the State of Rhode Island, have invented a new and useful Improvement in Sleeve-Buttons; and we declare the following to be a specification thereof, reference being had to the accompanying drawings.

Like letters indicate like parts.

10 Figure 1 is a front elevation of our invention. Fig. 2 is a side elevation of the same. Fig. 3 is a plan of the under side of the shoe. Fig. 4 is a detail view.

15 Our invention is especially applicable to sleeve-buttons, but is also useful for collar-buttons and studs.

It relates to that class of non-separable buttons in which the shoe swings from a transverse to a vertical position upon the post for 20 the purpose of entering the button-hole, and is brought back to its transverse position to hold the button when placed in the cuff.

Our invention consists of a sliding post having a limited longitudinal motion within the 25 external or hollow post, being sustained at its inner end by a spring within the button-front, and carrying at its outer end a shoe hinged to it, and kept in engagement with it by the pressure of a spring within the shoe, as hereinafter 30 particularly described.

The button A has a hollow rectangular post, B. Within the hollow post B is a sliding post, C, which has a slight longitudinal motion, limited by the spring D, which, passing through the 35 aperture a at the inner end of the post C, extends from side to side within the button-front. At the outer end the post C has a square-faced head, E, through which, at b, it is pivoted by a pin, c, to the butts F of the shoe G. A flat 40 spring, H, extends across the inner side of the shoe and engages with the head E of the post C to hold it in the desired position. By means of this arrangement of the parts the shoe may occupy either of the positions indicated in Fig.

2, the three exposed sides of the head E being 45 made plane surfaces for the purpose of such engagement. When the shoe is brought into position parallel with the button-front the head E of the post C lies flush with the outer end of the hollow post B, being drawn down into 50 the post B as far as possible by the action of the spring D; but when the shoe is tilted to a vertical position beside the post B the inner post, C, is slightly drawn out by the leverage 55 of the shoe, which finds its fulcrum on the edge of the external post in being swung over. This variation in the length of the post is the essential feature of our invention.

A radical defect in all buttons of this class, as heretofore made, has been that the post has 60 too great length. It must be of sufficient length not only to receive the folds of the cuff brought together to be buttoned, but also to furnish a clear space beyond the cuff for the tilting of the shoe; but when the shoe is turned back in- 65 to its transverse position across the end of the post, the post, because of its great length, projects too far, and the button does not set snugly 70 against the cuff, but presents an untidy appearance. Our invention wholly obviates this difficulty, because when the shoe is tipped to enter the button-hole the post is elongated by the drawing out of the inclosed post, as described, and when the button is in place and the shoe 75 is turned back to its former position the inner post is drawn back within the external post and the button sets snugly against the cuff.

We claim as a novel and useful invention and desire to secure by Letters Patent—

The improved button herein described, con- 80 sisting of the button-front A, posts B C, springs D H, and tilting shoe G, all arranged and operating substantially as specified.

JOHN HANCOCK.
LEVI RICHARDS.
